UNITED STATES PATENT OFFICE.

PAUL LIEBERKNECHT, OF CHEMNITZ, GERMANY, ASSIGNOR OF ONE-HALF TO ERNST BOESSNECK GESELLSCHAFT MIT BESCHRANKTER HAFTUNG, OF EINSIEDEL, NEAR CHEMNITZ, GERMANY.

DECKER GUIDE FOR KNITTING MACHINES.

Application filed January 21, 1927, Serial No. 162,547, and in Germany May 12, 1926.

The deckers used for narrowing and widening operations in knitting machines are usually carried by slidable rods which, to allow easy movement, must have a small 5 amount of free play. The oscillatory movements set up owing to the free play are magnified in the deckers so that the needles of the latter do not reliably cooperate with the knitting needles with the result that 10 stitches are often missed and needles bent.

The object of the present invention is to remedy this defect, and the invention consists in providing additional decker guides which are spaced from the carrying rods so 15 that oscillatory movement of the deckers can be effectively prevented without particular care being taken in the fitting up of the carrying rods.

Fig. 1 of the accompanying drawings represents a cross-section of one arrangement according to the invention,

Fig. 2, a front view of the same,

Fig. 3, a cross-section of a second arrangement,

Fig. 4, a front view of the latter,

Fig. 5, a cross-section of a third arrangement, and

Fig. 6, a front view of Fig. 5.

The deckers *b* are carried by rods *a* which 30 are arranged to slide in supporting arms *h*. In the arrangement according to Figs. 1 and 2, the deckers are formed with tail pieces *c* which bear against a stationary guide rail *e* and slide along the latter.

While the decker tail bears against one side 33 of the guide rail, a bracket *d* on the tail engages the opposite side of the same so that oscillatory movements of the decker needles about the carrying rods will be prevented.

In the construction according to Figs. 3 and 4, the carrying rods *a* are arranged higher up the arms *h* so that the guide rails *e* can be arranged underneath the same. The decker plates are lengthened to correspond. The bracket *d* is employed also in this construction.

In the arrangement according to Figs. 5 and 6 the brackets *d* are omitted, and the decker plates are guided between two rigid 50 rails *g* and *f*.

I claim:

1. In a straight-bar knitting machine, the combination with deckers mounted on slid- 55 able carrier rods, of guide rails arranged so as to support the deckers and prevent os- cillatory movements.

2. In a knitting machine with decker plates, a guide rail arranged so as to sup- 60 port the decker plates, and brackets secured to said plates so as to engage the reversed side of the guide rail.

3. In a knitting machine with decker plates, rails arranged above and below said plates so as to support the same and pre- 65 vent oscillatory movements.

PAUL LIEBERKNECHT.
